Inventor:

Emil Dittmann.

UNITED STATES PATENT OFFICE

EMIL DITTMANN, OF PLON, GERMANY

BOOKMARKER

Application filed September 6, 1930, Serial No. 480,159, and in Germany September 14, 1929.

This invention relates to a book-marker of the kind comprising a tapered tongue adapted to rest loosely on the leaves of the open book, to be deflected by and to slip past overturned leaves, and then to drop back into marking position, the tongue being adjustably connected to a supporting strip placed between the leaves and the book cover.

10 According to the invention the supporting strip is formed with an upturned end portion provided with parallel, longitudinal slits, and the tongue is held by a cord or the like which engages adjustably in said 15 slits.

Fig. 1 of the accompanying drawings is a perspective view showing the book-marker in use,

Fig. 2 is a similar view of the book-marker seen from a different point of view,

Fig. 3 is a sectional top view of the book-marker, and

Fig. 4 is a sectional side view of the same.

The book-marker comprises a supporting strip *a* having an upturned end portion *b* which is formed with two parallel, longitudinal slits *c*. The marking member consists of a tongue *d* which is formed near one end with two apertures *e* arranged at the same distance apart as the slits *c*. The tongue is held by a cord or chain *f* which engages in the apertures *e* and slits *c* and which is adjustable along the latter.

35 The supporting strip *a* is arranged at the right-hand side of the book between the leaves and the cover with the end portion *b* placed against the top edge of the book. The marking tongue *d* is placed loosely on the top leaf of the open book. As each leaf 40 is turned over it automatically deflects the tongue which falls back into marking position on the new leaf. The cord *f* controls the tongue and slides down the slits *c* in proportion as the leaves are turned over.

45 The tongue is made of transparent material so that the print can easily be seen through it. The right hand edge of the tongue is rounded off towards the free end as illustrated, so that it will easily slip past 50 the edges of the overturned leaves.

The cord or chain is preferably formed into a loop which is passed through the slits *c* and apertures *e* and which engages the strip and tongue portions intermediate thereof.

55 The cord may be elastic and fastened to the tongue and supporting strip so as to have a tendency to raise the tongue, thereby facilitating its slipping past the edges of the overturned leaves.

I claim:

A book-marker of the character described, comprising a supporting strip having an upturned end portion formed with parallel, longitudinal slits, a marking tongue formed near one end with apertures arranged at the same distance apart as the slits of the supporting strip, and a connecting cord formed into a loop passing through said slits and apertures and engaging the strip and tongue portions intermediate thereof.

EMIL DITTMANN.
